UNITED STATES PATENT OFFICE.

CHARLES P. VOGEL AND ALBERT C. VOGEL, OF MILWAUKEE, WISCONSIN, ASSIGNEES,
BY MESNE ASSIGNMENTS, TO MACHINERY DEVELOPMENT COMPANY, OF MIL-
WAUKEE, WISCONSIN, A CORPORATION OF WISCONSIN.

LEATHER-WORKING MACHINE.

Application filed May 14, 1927, Serial No. 191,413. Renewed May 4, 1928.

The invention relates to leather-working machinery.

The object of the invention is to provide a machine for treating leather and more particularly one for use in the setting out, stretching and the securing of leather to a setting-out board in an efficient manner.

The invention further consists in the several features hereinafter set forth and more particularly defined by claims at the conclusion hereof.

In the drawings Fig. 1 is a side elevation view of a machine embodying the invention, parts being broken away;

Fig. 2 is a plan view of the machine with the motor removed;

Fig. 3 is a vertical sectional view taken on the line 3—3 of Fig. 1;

Fig. 4 is a detail view showing a modified form of table-lifting mechanism;

Fig. 5 is a detail plan view of a part of the carriage;

Fig. 6 is a side view of a part of the carriage and a sectional view through the clamping member;

Fig. 7 is an end view of a part of the carriage;

Fig. 8 is a sectional view through the carriage, taken on the broken line 8—8 of Fig. 6;

Fig. 9 is a detail view of the table-locking mechanism.

Referring to the drawings, the numeral 10 designates the frame of the machine, 11 a stationary pedestal, 12 a pedestal or spindle 35 slidably mounted in said pedestal 11 and having a table-supporting frame 13 secured thereto, 14 a table having a central spindle 15 journaled in said pedestal 12 and provided with radially spaced sets of rollers 16 running on the top surface of the frame 13. Thus the table is free to rotate on the pedestal but to hold it in either one of two positions a pair of bevelled locking lugs 17 are mounted beneath the table at diametrically opposite

45 points, and a spring-pressed detent 18 mounted on the frame 13 is adapted to engage between either pair of said lugs to lock the table against turning. As shown in Fig. 9, a spring 19 acts to move said detent 18 to a locking position and a lever 20 pivotally connected at one end to the frame 13 and intermediate its ends to said detent has its free end under the control of the operator to release said detent so that the table may be turned to re-

verse the position of the setting-out board 55 22 and the hide 23 thereon.

A clamping member 24 extends transversely across the machine and is urged downwardly by a plurality of springs 25, said member being limited in its movement in a suitable 60 manner, as by means of a stop member 26 adjacent each end, extending through a vertically disposed slot 27 and secured to brackets 28. The board 22 with the hide 23 thereon is clamped between the member 24 and the 65 table 14 by raising the table until the hide engages the member 24 and moves it upwardly putting the springs 25 under compression.

The means shown in Figs. 1 and 3 for raising the table 14 comprises a pair of levers 29 70 on each side of the machine, one lever of each pair being pivotally mounted intermediate its ends upon a transversely disposed shaft 30, the other lever of each pair being pivotally mounted intermediate its ends upon a transversely disposed shaft 31, the inner ends of each of the levers being connected to the frame 13 by a link 33 having an adjustable turnbuckle 34, the inner ends of the levers of each pair being respectively pivotally connected to a link 35 which is pivotally connected to the intermediate portion of a lever 36 pivoted at 37 upon the frame of the machine. The spaced levers 36 are connected together at their free ends by a tie-rod 36' and 75 a transversely disposed treadle member 38 so that depression of the treadle, by the operator, causes the downward swinging movement of the inner ends of each pair of levers 29 and an upward swinging movement of the outer 80 ends of said levers which, through the links 33, is transmitted into an upward movement of the frame 13, pedestal 12 and the table 14 thereon to produce the clamping engagement previously described. The weight of the 85 table, its support and the linkage is counterbalanced by a counterbalance weight 39 mounted on the treadle.

In Fig. 4 a modified form of table-raising linkage is shown wherein the leverage is increased by the interposition of gearing between the links 33 and the levers 29'. This gearing includes a segmental gear 40 formed at the outer end of each of the levers 29' which are otherwise similar to the levers 29 and similarly connected to the links 35. The gear portion 40 meshes with a gear 41 which meshes with a fixed rack 42 and carries a 100 105

crank-arm 43 to which the lower end of the link 33 is connected so that when the operator depresses the treadle the upward swinging movement of the toothed ends of the levers 5 29' rotates the gears 41 so as to swing the arms 43 upwardly and hence move the links 33 and the parts including the table 14 upwardly to accomplish the clamping engagement of the hide and board between the table 14 and 10 clamping member 24.

For pressing the hide upon the board and simultaneously stretching the same, a roller 44 is journaled on a reciprocating carriage, said roller having spirally disposed blades 15 45 arranged in herringbone relation and substantially straight blades 46 radially disposed between the convolutions of said spiral blades.

The carriage includes end plates or frames 47 and 48 connected together by tie-rods 49 and having shafts 50 carrying rollers 51 running in a track 52 formed on the top of a longitudinally extending guide 53. The roller 44 has a shaft portion 54 upon which a roller 55 is mounted, said roller sliding in 25 the way formed by the guide 53 and a guide 56 and being journaled at its outer end in a split bearing 57 on each end of the carriage. The frame 47 has a motor pad portion 58 formed thereon upon which an electric motor 59 is 30 mounted, its drive shaft 60 carrying a gear 61 meshing with a gear 62 on a shaft 63 journaled at its end portions in the frames 47 and 48 and carrying gears 64 meshing with gears 65 on the roller shaft whereby said roller 35 is rotated by said motor.

The carriage is reciprocated back and forth to move the roller over the work by means of a power-driven shaft 66 having a drive-pulley 67 mounted thereon and gears 68 meshing with gears 69 on a shaft 70 carrying fly-wheels 71, each provided with a crank-pin 72 operatively connected with one of the end frames of the carriage by a connecting-rod 73 and a pin 74 mounted in a lug 75 on each of 45 said end frames.

With the above construction for setting out and stretching the hide, the setting-out board, with the hide laid thereon in a pliable condition, is placed on the table in its lowered position and, according to one method, with adhesive between the board and the hide, the board and the hide being so placed on the table that when the table is raised to bring the member 24 into clamping operation, said member will extend lengthwise across the entire hide and beyond the midback portion. The raising of the table to a clamped position is so timed by the operator as to occur on the outward travel of the roller 44 so that with 55 the hide clamped down the rotating roller is brought into pressing engagement with the hide throughout its entire length and while so related is moved from the midback portion of the hide out over the flanks by 60 65 the drive connection previously described,

with the result that the hide is secured to the setting-out board and simultaneously stretched in all directions along the engaging front of the roller by the action of the straight and curved blades, and where adhesive is used between the hide and the board this stretching action takes place progressively along a continuously shifting front instead of between said roller and the clamping member. Thus a full half of the hide is operated upon by the roller and then the table 14 is lowered before said roller can travel back over the hide, the detent is released and the table turned through a half circle and the detent allowed to snap into locking engagement with the set of lugs 17, then in position to receive it, and the table is again raised to bring the hide and board into clamping engagement with the member 24 at the opposite side of and beyond the midportion of the back and at a time when the roller 44 is starting on its outward stroke so that pressure of the roller upon the hide smooths and stretches out the remainder of the hide in the manner previously described in connection with the operation on the first half of the hide. The machine, of course, is not to be limited in its use to the specific method above described, as the hide may be shifted to other positions relative to the roller, if desired. It is also preferred to impart a much faster speed of rotation to the roller compared to its motion of translation over the hide and this insures an efficient pressing action of the roller as it travels slowly over the hide and permits the operator to more readily time his operations of raising and lowering the table. The degree of pressure exerted by the roller 44 is under the control of the operator by the pressure he exerts on the treadle member 37 and the setting-out board is preferably of fibreboard, somewhat yieldable or pliable to prevent injury thereto by the roller and to accommodate for irregularities in thickness of the hide.

We desire it to be understood that this invention is not to be limited to any particular form or arrangement of parts except in so far as such limitations are specified in the claims. 105

What we claim as our invention is:

1. In a machine of the character described, the combination of a supporting table, a hide-clamping means, a carriage mounted above the table, a pressing-and-stretching roller journaled in said carriage and extending across said table, drive means for said roller mounted on said carriage, means for reciprocating said carriage, and means under the control of the operator for moving said table relative to said roller.

2. In a machine of the character described, the combination of a supporting table, a spring-pressed hide-clamping member extending across said table and cooperating therewith to secure the hide thereto, a carriage

mounted above the table, a pressing-and-stretching roller journalled in said carriage, drive means for said roller including an electric motor mounted on said carriage, means 5 for reciprocating said carriage, and means under the control of the operator for moving said table relative to said clamping means and said roller.

3. In a machine of the character described, 10 the combination of a vertically-movable table support, treadle-operated means for moving said support, a table revolubly mounted on said support, means for holding said table against rotary movement relative to said support, a hide-clamping member extending 15 across and above said table and cooperating therewith to secure a hide thereto, a carriage mounted above the table, a pressing-and-stretching roller journalled in said carriage 20 and extending across said table, drive means for said roller mounted on said carriage, and means for reciprocating said carriage.

4. In a machine of the character described, 25 the combination of a vertically-movable table support, treadle-operated means for moving said support, a table revolubly mounted on said support, means for holding said table against rotary movement relative to said support, a hide-clamping member extending 30 across and above said table and cooperating therewith to secure a hide thereto, a carriage mounted above the table, a pressing-and-stretching roller journalled in said carriage, drive means for said roller including 35 an electric motor mounted on said carriage, and means for reciprocating said carriage.

5. In a machine of the character described, 40 the combination with a hide-supporting table and a clamping means associated therewith, of two sets of spaced guides, a carriage having rollers mounted to run on one of each set of guides, a pressing-and-stretching roller having rollers running between each set of 45 guides, means for rotating said pressing-and-stretching roller, and means for moving said pressing-and-stretching roller along said guides.

6. In a machine of the character described, 50 the combination with a hide-supporting table and a clamping means associated therewith, of two sets of spaced guides, a carriage having rollers mounted to run on one of each set of guides, a pressing-and-stretching roller having rollers running between each set of 55 guides, drive means for said pressing-and-stretching roller mounted on said carriage, a power-driven shaft, and means operatively connecting said shaft with said carriage for reciprocating said carriage.

7. In a machine of the character described, 60 the combination with a rotating and movable pressing-and-stretching roller, of a hide-supporting table, means for raising and lowering said table comprising a support for

said table, two sets of levers arranged in spaced relation on opposite sides of said support and operatively connected thereto, a pair of treadle-operated levers, and a connection between each of said treadle-operated levers 70 and the levers of each set of the first-named levers, and means for counterbalancing the weight of said table and said table-raising-and-lowering means.

8. In a machine of the character described, 75 the combination with a rotating and movable pressing-and-stretching roller, of a hide-supporting table, means for raising and lowering said table comprising a support for said table, two sets of levers arranged in spaced 80 relation on opposite sides of said support and operatively connected thereto, a pair of treadle-operated levers, and a connection between each of said treadle-operated levers and the levers of each set of the first-named 85 levers, and a counterweight associated with said treadle-operated levers for counterbalancing the weight of said table and said table-raising-and-lowering means.

9. A machine for pressing and stretching a 90 hide on a setting-out board to set out the hide on the board in a stretched condition, comprising means for supporting the setting out board in such a manner that the setting-out board with the hide thereon may be easily 95 removed from the machine for drying upon the completion of the pressing and stretching operation, means for simultaneously stretching the hide and pressing the same against the board, and means for preventing 100 slippage of the hide during the stretching and pressing operation.

10. A machine for pressing and stretching a hide on a setting-out board to set out the hide on the board in a stretched condition, comprising means for simultaneously stretching the hide and pressing the same against the board, means for supporting the setting out board in such a manner that the setting-out board with the hide thereon may be easily removed from the machine for drying upon the completion of the pressing and stretching operation and may be shifted with the board to different positions relative to the pressing and stretching means, and 105 means for preventing slippage of the hide during the stretching and pressing operation.

11. A machine for pressing and stretching a hide on a setting-out board to set out the hide on the board in stretched condition, comprising a supporting table for the setting-out board and hide shiftable to present different portions of the hide for working, means for holding the hide against slippage in any 110 position of said table, a pressing and stretching roller engageable with the portion of the hide presented for working, means for rotating the roller, and means for causing relative feeding movement between the roller 115 120 125 130

and that portion of the hide presented for working.

12. A machine for pressing and stretching a hide on a setting-out board to set out the hide on the board in a stretched condition, comprising supporting means for the setting-out board and hide, a stretching and pressing roller engageable with the hide, said supporting means and said roller being relatively movable whereby said roller may be engaged with or disengaged from the hide, and clamping means for the hide engageable therewith when the roller engages the hide and disengaged therefrom when the roller is free of the hide.

13. A machine for pressing and stretching a hide on a setting-out board to set out the hide on the board in a stretched condition, comprising a supporting table for the board and hide, a pressing and stretching roller engageable with the hide, means for rotating the roller, means for advancing the roller relative to the surface of the hide, means for raising and lowering the table to cause the roller to engage with and to be disengaged from the hide, and clamping means engageable with the hide in the raised position of the table and disengageable therefrom upon the lowering of the table.

14. A machine for pressing and stretching a hide on a setting-out board to set out the hide on the board in stretched condition, comprising a shiftable table for supporting the setting-out board and hide, a pressing and stretching roller engageable with the hide, means for rotating the roller, means for moving the table and roller relative to each other to bring the roller into and out of operative contact with the hide, means for moving the table and roller relative to

each other to advance the roller over the hide, and means for clamping the hide against slippage during the pressing and stretching operation.

15. A machine for pressing and stretching a hide on a setting-out board to set out the hide on the board in a stretched condition, comprising a supporting table for the board and hide, clamping means engageable with the hide for holding it against slippage and for preventing displacement of the setting-out board on the table, a pressing and stretching roller engageable with the hide, means for rotating the roller, and means for causing relative feeding movement between the surface of the hide and said roller.

16. A machine for pressing and stretching a hide on a setting-out board to set out the hide on the board in a stretched condition, comprising supporting means for the setting-out board and hide shiftable to different working positions, hide-clamping means, and a pressing and stretching roller engageable with the hide and having means for stretching the hide laterally and longitudinally.

17. A machine for pressing down and stretching a hide on a setting-out board, comprising stretching means, and means for supporting and holding the board and the hide against slippage while being acted upon by said stretching means, said hide and board being releasably held by said supporting and holding means so as to be easily removed from the machine for drying upon the completion of the stretching operation.

In testimony whereof, we affix our signatures.

CHARLES P. VOGEL.

ALBERT C. VOGEL.
